UNITED STATES PATENT OFFICE.

ARTHUR K. MILLER, OF NEW YORK, N. Y.

DESIGN FOR A LAMP.

SPECIFICATION forming part of Design No. 31,182, dated July 11, 1899.

Application filed May 12, 1899. Serial No. 716,590. Term of patent 14 years.

To all whom it may concern:

Be it known that I, ARTHUR K. MILLER, a citizen of the United States, and a resident of New York, (Brooklyn,) in the county of Kings 5 and State of New York, have invented a new and original Design for a Lamp, of which the following is a specification.

The leading feature of my design comprises the body portion of the lamp, consisting of 10 the two cylinders 1 and 2 and the flame-chamber 3, located in the front of the body portion and having the chimney on its top, as shown in the accompanying drawings, which form part of this specification, and which, taken in 15 connection with this specification, will enable any one to construct and use my design.

In said drawings, which illustrate and embody my design, Figure 1 is a front elevation. Fig. 2 is a top view thereof. Fig. 3 is a side 20 elevation. Fig. 4 is a rear view. Fig. 5 is a bottom plan view.

The cylinders 1 and 2 constitute the body of the lamp, situated a slight distance apart,

and projecting from the cylinders 1 and 2, and forward thereof, is the flame-chamber 3, 25 having the glass or lens 4 in front. This flame-chamber is supported by a post 5, located between and connected to the cylinders 1 and 2. The flame-chamber is provided with the chimney 6 on its top, and the cylinders 1 and 30 2 are provided with the tops 7 and 8, respectively.

While my design is particularly intended to be applied to gas-lamps, it is apparent that it may be also applied to oil-lamps.

What I claim, and desire to secure by Letters Patent, is—

The design for a lamp, substantially as shown and described.

In testimony whereof I have signed my 40 name to this specification in the presence of two subscribing witnesses.

ARTHUR K. MILLER.
